United States Patent Office

Des. 185,230
Patented May 19, 1959

185,230

ASH RECEPTACLE OR SIMILAR ARTICLE

William S. Pearson, Baltimore, Md.

Application October 1, 1958, Serial No. 52,838

Term of patent 14 years

(Cl. D85—2)

I claim:

The ornamental design for an ash receptacle or similar article, substantially as shown.
